UNITED STATES PATENT OFFICE.

JOHN PETER WEIS, OF NYACK, NEW YORK, ASSIGNOR OF ONE-HALF, BY MESNE ASSIGNMENTS, TO METROPOLITAN SEWING MACHINE CORPORATION, OF NYACK, NEW YORK, A CORPORATION OF DELAWARE.

STOP-MOTION.

1,352,333.

Specification of Letters Patent.

Patented Sept. 7, 1920.

Original application filed October 16, 1914, Serial No. 867,005. Divided and this application filed April 29, 1916, Serial No. 94,355. Renewed December 24, 1919. Serial No. 347,191.

To all whom it may concern:

Be it known that I, JOHN PETER WEIS, a citizen of the United States, residing at Nyack, in the county of Rockland and State 5 of New York, have invented certain new and useful Improvements in Stop-Motions, of which the following is a specification.

This invention is an improvement in stop motions for sewing and other machines and involves constructional arrangements whereby thorough and constant lubrication is obtained for the stop-motion parts. The sewing machine and stop motion illustrated are high-speed mechanisms in which serious 10 heating would occur were the necessary parts not thoroughly and constantly lubricated while the mechanisms are in action. My present invention in stop motions is widely applicable to machine drive-shafts 15 other than those of sewing machines.

This application is a division of my application Serial No. 867,005 for sewing machine and cutting mechanism therefor, filed October 16, 1914, and which describes features of improvement on the combined cutting-and-sewing machine shown in my United States Patent No. 1,114,082 of October 20, 1914. The lubricating system here- 20 in described forms the subject-matter of my application Serial No. 94,354, filed April 29, 1916.

In the accompanying drawings forming part hereof,

Figure 1 is a top plan view of a portion 35 of the combined cutting-and-sewing machine mentioned. This view shows two sewing machine heads and for each head one member of a stop-motion. The view is particularly useful in locating parts illustrated 40 in other figures.

Fig. 2 is a lengthwise sectional view of one of the sewing machine heads at line 2-2 of Fig. 1. This view shows an oil reservoir and pump carried by one of the 45 sewing machine heads, the construction and arrangement of the top drive-shaft and of the looper shaft and of various connections between the two, together with the means for driving the oil pump and a portion of 50 the stop motion, in lengthwise central sec-

tion, for the top drive-shaft of a sewing machine.

Fig. 3 is a view partly in side elevation and partly in vertical section at line 8-8 of Fig. 1, and shows the top drive 55 shaft of a sewing machine head with a stop motion therefor and a stop motion control lever provided with means for holding a shock-absorbing body of oil.

Fig. 4 is a rear end view of the stop- 60 motion control lever and of its pivoted stop finger.

Fig. 5 is a side elevation of the rearward end portion of the stop-motion control lever and of the other parts shown in Fig. 9. 65

Fig. 6 is an elevational view partly in full lines and partly in lengthwise central section, of a thimble-forming part of the construction of the rearward oil-receiving and oil-holding end of the stop motion control lever. 70

Figs. 7 and 8 are respectively side and end elevations of a perforated sleeve for receiving the thimble shown in Fig. 6, the sleeve being adapted for a threaded connection with a chamber in the rearward end 75 of the aforesaid lever.

Fig. 9 is a view partially in elevation and partly in vertical central section, at a line corresponding to line 14-14 of Fig. 10, 80 and shows a rearward portion of the top shaft of a sewing machine head provided with a pulley for driving such shaft and for clutching the stop motion therefor. The view also shows certain details of the stop motion, including a recess for a brake shoe 85 omitted from the view.

Fig. 10 is a view partially in elevation and partly in transverse section at line 15-15 of Fig. 9, and shows the driving and 90 clutch pulley together with details of the stop motion. This view shows the stop-motion balls in a clutched position by engagement with a ball-retaining ring clamped in the belt wheel.

Fig. 11 is a view similar to Fig. 10 but shows stop-motion wedges and balls in non-clutching position. 95

Fig. 12 is an end elevation of the rearward end portion of the top drive shaft and illus- 100

trates in end view a lengthwise-extending key on the rearward end of the drive shaft.

Fig. 13 is a side elevation of the rearward end portion of said drive shaft, and shows the lengthwise-extending key together with wedge-receiving pockets in a portion of the drive-shaft.

Fig. 14 is a tubular sleeve of varying diameters, a portion of which forms a ball retainer, and another portion of which forms a stop tooth. This sleeve is a member of the stop motion and has portions acted on by a brake shoe.

Fig. 15 is a transverse sectional view of said sleeve at line 20—20 of Fig. 14.

Fig. 16 is an end elevation of the rearward end of the top drive-shaft and of the driving and clutch pulley in assemblage with the parts shown in Figs. 13, 14, 15, and other figures.

Fig. 17 is a perspective view of one of the ball-receiving wedges forming part of the stop motion.

Fig. 18 shows in two views a brake shoe forming a part of the stop motion.

Fig. 19 is a view partly in elevation and partly in transverse central section at line 24—24 of Fig. 9, and illustrates the construction of the rear end bearing for the stop sleeve shown in Fig. 9 for the rearward end portion of the top-shaft. The brake shoe is indicated in plan by dotted lines.

Fig. 20 shows in elevation and end view a brake-shoe pressure-plug forming part of the stop-motion.

Fig. 21 is a perspective view of the brake-shoe lifting lever forming a part of the stop motion.

Fig. 22 is an enlarged view of the needle holder guide, to show more clearly the oil conduits in these parts.

Referring to the drawings, the two sewing machine heads together with their respective stop-motions are identical. Description of one sewing machine and of one stop-motion will therefore be sufficient. The sewing machine head comprises an upper horn A, an under horn A', and a connecting trunk a; the horns and trunk having communicating chambers. The outer wall of the trunk comprises an inwardly projecting boss a' in the inward end of which stop-motion members are arranged in operative relation to the rear end of the top or needle-bar drive-shaft. The upper side of the upper horn A is provided with a covered opening at a² for access to the chamber of the trunk, and the outer end wall is provided with an opening a³ through which the lubricant is poured into an oil container carried by a lower part of the trunk. The rear wall of the trunk is also provided with a covered opening a⁴ into a lengthwise-extending chamber of the boss a' for observation of the lubricant through the transparent cover a⁵ in the chamber of the

boss a', the rearward portion of such chamber forming an oil space and the forward portion forming a housing. The top drive-shaft and the looper shaft hereinafter described are both tubular and each is inclosed between its ends for the greater part of its length in tubes hereinafter described, which are centered and held in the lengthwise-extending chambers of the horns by set-screws a⁶ through the horns and impinging on the outer surfaces of the tubes.

Sewing-machine stop-motion.—The shaft extension 25^a has its ball cranks 35 spaced apart one from the other, and rearwardly of these cranks it has an enlarged portion 91 formed circumferentially with three wedge-receiving pockets 92 at 120° apart, to receive the segmental wedges 93, the curved wall of each of which from its butt to its pointed end, is grooved at 94 in the direction of the curvature of the wedge to receive balls. The cross-section of the pockets is shown in Figs. 10 and 11, which also show the cross-section of the wedge shown in perspective in Fig. 12. The curved grooves 94 are eccentric to the axis of the top shaft, and the outward edges of the side walls 95 of each groove are concentric with the top shaft axis and flush with the periphery of the enlargement 91. A stop sleeve 96 (Figs. 9, 10, and 14) has two interior and two corresponding exterior diameters. Portion 97 of the sleeve fits freely on the top-shaft enlargement 91 and holds the wedges 93 in the pockets 92. Portion 97 of sleeve 96 is provided with three openings 98 through its annular wall, spaced apart 120° to receive the balls 99, each of which lies projectingly in an opening 98, and also lies in a groove 94 of a wedge 93. A ball retaining ring 99^a forms part of the belt-wheel 100 which is made in two parts secured laterally together by screws 101, the ball retaining ring being secured fixedly between them. The belt-wheel has a hub 102 projecting from each of its sides, the hub fitting loosely and running on the sleeve 96 which is exteriorly reduced in diameter at 103, 103, and exteriorly provided with an interposed stop tooth 104 between the reduced portions 103, 103 which are of uniform exterior diameter. The tooth 104 is formed by grooving the outer wall of the sleeve annularly and eccentrically to its lengthwise axis between the portions 103. This eccentric groove is indicated by 105. The interior annular wall of the reduced portion of sleeve 96 has a lengthwise-extending key-slot 106 to receive a radially projecting key 107 formed on the outer end 108 of the top shaft extension 25^a adjacent the enlargement 91 (Figs. 12, 13 and 15). The interior wall of the reduced portion of the sleeve 96 is indicated by 109. The sleeve 96 is provided at the end of its reduced portion with a pin 110 extending in the direc-

tion of the length of the sleeve. One end of a coil spring 111 which is the stop-motion starting spring, is secured to this pin, and the other end of the spring is connected by a 5 pin 112 to the keyed portion 107 of the top shaft. An end bearing 113 for the sleeve 96 is cut out at 114 to receive a brake shoe, and also at 115, and is formed with a bore 116 (Fig. 19) wherein portions of the reduced 10 portions 103 with other portions of the sleeve freely rotate in exposure to the brake shoe. A brake-shoe 117 (Figs. 2, 3 and 18) is mounted in the cut-out 114. The shoe has a lining 118 of Babbitt or other metal or 15 material, and on its upper or back side has a slot 119 which receives the end 120 of a pressure-plug-lifting lever 121 (Figs. 3 and 21) which at 122 is pivoted in a housing for the stop-motion with one end projecting for 20 actuation. Such housing is the front end portion of the chambered boss a' . The top of the brake shoe is concaved at 124 at right-angles to the slot 119 to receive the convex head 125 of the pressure-plug 126, the head being slotted at 127 to receive the end 120 of the lever 121. A coil spring 128 (Fig. 3) surrounds the upwardly-extending stem of the pressure-plug 126 and a hollow screw 129 surrounding the stem of the pressure 30 plug is mounted in the housing mentioned to regulate the pressure of the spring $\frac{1}{2}$ the under end of which bears on the flange 123 of the pressure plug head. The housing is centrally chambered at 130 to receive the 35 bearing 113 for the assembled sleeve 96 and shaft end 108 (Figs. 2, 3 and 9). The housing on its side opposite the pressure plug or on its underside in the form shown, has a radial slot 131 which communicates with the cut-out 115 formed in the bearing 113. The housing, adjacent the pressure plug, is slotted at 132 to receive the pressure-plug-lifting lever 121 which at 122 is pivoted between side walls of the slot. The oil chamber 27 is at the outward end of the chambered boss or housing a' and is supplied with lubricant from the oil tube 11, the upper end of which overhangs and discharges into the oil-feed opening 12 formed vertically in the upper wall of the housing. 50

Stop-motion control.—The sewing-machine trunk is provided with a bulging projection 134 at its upper front side. The front wall of the bulging projection is vertically slotted at 135 to receive the hub 136 of the stop-motion control lever 137 which is formed forwardly of its hub with a transverse opening 138 into which projects the end of an adjusting screw 139 to engage the end 140 of a trip lever 141, the end 140 projecting laterally into the hole 133 in opposition to the end of the adjusting screw 139. The stop-motion control lever 137 is fixed on a transverse rocker shaft 142 by set screw 143. The ends of the

rocker shaft 142 are journaled in bearings in the side walls of the slot 135 of projection 134, and the trip lever 141 which is loosely fulcrumed on the rocker shaft 142 is provided with an upwardly and forwardly projecting arm 145, the free end of which overlaps the forwardly projecting arm of the pressure-plug lever 121. The rear arm 144 of the controlling lever 137 projects into the chamber of the trunk and its upper side is recessed at 145 to hold a wire basket or the like 146 filled with filtering material 147, the basket or container being held in place by a staple 148. The recess 145 and filtering material hold lubricant supplied by the oil pump referred to, the lubricant flowing into recess 145 from the conduit 90. An oil canal 149 extends forwardly from the bottom of the lubricant recess 145 through the end wall of a bore 150 in the rear end of the controlling-lever arm 144. The outer portion of this bore is tapped to receive a hollow annular bushing 151 having in its forward end a plug 152 secured to the bushing by a transverse pin 153. The plug has an integral rearwardly-extending stem 154. The outer or rearwardly-extending end of the bushing is threaded so as to be screwed into the tapped end of the bore 150, and forwardly of its threaded portion the bushing has a reduced exterior diameter through the side walls of which, just inwardly of the inner wall of the plug 152, oil holes 155 are formed. The annular wall of the bushing also has a series of annularly arranged oil holes 156 adjacent the inward end of its threaded portion. A sliding thimble 157, the rearward closed end of which is rounded off at 158, is mounted in the bore of the bushing 151, the tubular wall 159 of the thimble sliding freely in the bushing, and the thimble serving as a valve to cover and to uncover the series of oil holes 156, but not to cover or uncover the oil holes 155 which are diametrically aligned one with the other. A coil spring 160 surrounds the plug stem 154, abuts against the rearward wall of the plug, and also abuts at its other end against the end wall of the thimble, and this spring 115 has a strength just sufficient to push the sliding thimble outwardly to uncover the oil holes 156 when exterior pressure on the thimble end is relieved. The outwardly-rounded head 158 of the thimble is always 120 pressed outwardly by the spring 160 against the opposed end 161 of a stop finger 162 which by pin 163 is pivoted to a bracket 168 carried by the rear end of the arm 144 of the stop lever 137. The lower end of 125 the stop finger is provided with a transverse pin 164 projecting on both sides, and each projecting end of the pin has connected to it a coil spring 165. The upper end of each spring is attached to the pro- 130

jecting neck ends 166 of the pin 163. The springs thus mounted are under tension and hold the stop finger 162 with the pivot pin 163 abutting against the under wall of 5 a slot 167 formed through and elongated in the direction of the length of the stop finger, by the spring 165 and slot 167 construction. The stop finger 162 permits the stop lever 137 and its arm 144 to assume 10 the position shown in Fig. 3 even if the tooth 104 is not in exact position for reception of the stop finger 162 so that it will enter the eccentric cut 105 to engage the tooth 104 on its next rotation. The bracket 15 168 carried by the stop lever arm 144 is slotted at 169 to receive the stop finger, the head 170 of which coacts with the stop tooth 104. The upper side of the bracket 168 projects upwardly into a slot 171 of 20 the housing or boss a' , and the head of the stop finger reaches the stop tooth 104 of the stop sleeve 96 through the communicating slots 171, 181 and 115.

The body of oil or other lubricant contained within the thimble 157 and the bushing 151 and the plug 152, is a vitally important feature of and factor in the stop-motion mechanism. This body of oil which I show by dots marked C, constitutes a 25 shock-absorbing cushion, which cushion is characterized by the power to absorb shock without any resultant rebound. Oil in chamber 27 of the boss reaches opposing surfaces of the stop motion through the space 30 (Fig. 2) between the outer surface of the outer end of the top shaft extension 25^a and the inner surface of the sleeve 96. This space as an oil-receiving conduit is seen in Figs. 2 and 16 where it is indicated by 35 172. Thence the oil finds its way between opposing surfaces of parts and works in between the outer surface of the enlarged portion 91 of the top shaft extension 25^a and the inner surface of the enlarged portion 97 of sleeve 40 96, reaching the balls 99 and the wedges 94 and the walls of the wedge-receiving pockets 92.

The mode of operation of the stop motion is as follows: As shown in Fig. 3 the stop 45 finger 162 is up against the stud 163 with its upper end in engagement with the stop tooth 104. The brake shoe 117 is in its lowermost position. The top shaft is rotatable in counter-clockwise direction as indicated by 50 the arrow in Fig. 3, and the shaft is in its stopped position. Assuming that the stop-motion control lever 137 has its outward or forward end lifted, then the stop finger 162 will be pulled down out of engagement with 55 the tooth 104. Simultaneously the arm 145 of the trip lever 141 will be depressed, pushing the forward end of the brake shoe lifting lever 121 downwardly and raising the pressure plug 126. Thereby the pressure of the 60 65 brake shoe on the clutch sleeve 96 is relieved.

The spring 111 (Figs. 9 and 16) instantly causes the stop sleeve 96 to rock, thereby forcing the balls 99 which project through the holes 98 in the stop sleeve to climb up from low to high position in the grooves 94 70 of the wedges 93. Thereupon, when the balls get into this high position they wedge between the wedges and the ball-retaining ring 99^a, and as this ring is clamped in the pulley 100, rotation of the pulley rotates the ball-engaging ring and thereby the rotational movement is imparted to the balls and the wedges and as the latter are in the ball-receiving pockets of the top shaft, rotation of the top shaft is effected. On the other hand, 80 whenever in the rotation of the top shaft the upper end of the stop finger is brought into eccentric groove 105 of the stop sleeve and rotation of the latter brings the tooth 104 against the stop finger, the stop sleeve 96 85 is rocked and its rocking movement carries the projecting balls 99 from the high points of the wedge grooves to the low points thereof, thus taking the balls out of contact with the ball-retaining ring. At the same time 90 the reverse movement of the stop-motion control lever which is required to thrust the upper end of the stop finger into the eccentric groove 105, raises the arm 145 of the stop lever 141 out of pressure contact with the 95 pressure plug lifting lever 121 and then the spring 128 expands and forces the brake shoe against the stop sleeve 96. The brake shoe presses against the reduced diametric portions 103 of the stop sleeve. The parts in 100 question are so timed that each opposite movement of the brake shoe and pressure plug and consequently of the pressure plug lifting lever 121, slightly precedes the initial 105 opposite movements of the stop finger in its engagement and disengagement with the tooth 104. The purpose of this timing is that the brake shoe in its braking movement against the stop sleeve 106 shall overcome 110 the tension of the spring 111 and the fact in 115 this connection is that when the tension of the spring 111 is relieved or as it is relieved gradually, the balls are shifted correspondingly out of interlocking relation to the ball-retaining sleeve and it is noticeable that the power transmitted through the balls to the shaft is under the control of the spring 111. The result of this is in practice that there is a minimum of shock.

I have above referred to the relation of the 120 cap 63 to the pulley or belt wheel hub 102. The belt wheel as shown has the ends of its projecting hub annularly grooved at 102^a at each end. The outward end of the cap 63 which is endwise slidable has an annular 125 opening, the annular edge of which faces the adjacent groove 102^a. The purpose of this is to prevent oil from the ball bearings 35 from flying onto the belt. At the other side of the pulley, the purpose of the corresponding 130

flange 102 is to prevent any oil getting into that groove from flying onto the belt.

The stop motion in the form shown is operable instantly to arrest the top drive shaft 5 at the completion of any revolution, and in the sewing machine stops the drive shaft with the needle up above the work.

What I claim is,—

1. The combination in any machine of a 10 rotary shaft with a stop motion mechanism constructed and operating to engage the shaft to stop its rotation and to release the shaft to permit its rotation, such mechanism comprising compressing members and means 15 for holding between them a shock absorbing quantity of oil; an oil supply mechanism; and a conduit connection between said means and mechanism.

2. The combination in any machine of a 20 rotary shaft with a stop motion mechanism constructed and operating to engage the shaft to stop its rotation and to release the shaft to permit its rotation, such mechanism comprising compressing members and means 25 for holding between them a shock absorbing quantity of oil; an oil pump; and conduit means for supplying the oil to the oil holding means.

3. The combination of a drive shaft; a 30 stop motion for the shaft; a stop motion control mechanism; and an oil supply pump mechanism comprising means for holding a shock-absorbing body of oil to relieve shock on the shaft, stop motion and stop motion 35 control.

4. The combination of a drive shaft; a stop motion for the shaft; a stop motion control mechanism; and means for supplying and holding a shock-absorbing body of oil 40 in the stop motion control mechanism; and means for automatically replenishing the oil forming said shock-absorbing body.

5. The combination of a rotary shaft with a stop motion comprising a brake shoe; a 45 brake-shoe lifting lever; a trip lever coöperating with the brake-shoe lifting lever; a stop-motion control lever; an endwise movable stop-finger for the stop-motion and constructed and operating to engage and disengage a toothed member of the stop motion and to coöperate with the stop-motion control lever; the latter being provided with fluid compressing members constructed to receive between them a volume of oil and one 55 of said members being movable and located to coöperate with the stop finger; and an oil pump.

6. The combination of a rotary shaft having a plurality of wedge-receiving pockets; 60 a grooved wedge for each pocket; a ball mounted in each wedge groove; an exteriorly toothed member having ball receiving holes and an interior lengthwise extending keyway; the shaft being formed with a lengthwise 65 extending key in the keyway; a ball re-

tainer; a spring connection between the shaft and the toothed member; a brake shoe and its operating mechanism; a stop-finger and actuating means therefor.

7. The combination of a pulley and a rotary shaft with a stop motion mechanism 70 comprising an annular ball retainer on which the pulley is fixed; a series of balls; a series of wedges on surfaces of which the balls are mounted; the shaft having wedge-receiving 75 pockets; an exteriorly toothed sleeve having ball-receiving holes through which the balls project, the sleeve being mounted between the wedges and the ball retainer; means for coöperatively connecting the shaft and said 80 toothed member; a stop-finger for engaging the tooth of the toothed member; a brake shoe; and brake-shoe operating mechanism.

8. The combination of a rotary shaft provided with a series of peripheral pockets 85 each for reception of a wedge; a ball on each wedge; an exteriorly toothed sleeve having ball-receiving holes and mounted on the shaft with the balls projecting; an annular ball retainer and pulley carrier; said sleeve 90 having a lengthwise extending keyway and the shaft being formed with a lengthwise extending key; the keyway and key when in working position having relative rotational relations with an oil-receiving space in the 95 way; operative connections between the shaft and toothed sleeve; a stop finger; stop-finger actuating mechanism; a brake shoe; and brake-shoe operating mechanism; the stop-finger actuating mechanism comprising an 100 oil reservoir and oil compressing members one of which is in coöperative relations to the stop finger.

9. The combination of a rotary shaft; a stop-motion mechanism therefor comprising 105 a stop finger; and a stop-motion control mechanism comprising a lever which has an oil container and oil compressing members one of which is movable and in operative relation to the stop-finger; and an oil pump. 110

10. The combination of a machine having a chambered member; a shaft bearing mounted in a part of the chamber of said member, a part of such chamber serving as an oil container; a stop motion for the shaft 115 mounted on the bearing and constructed for flow of oil from the reservoir to the stop motion parts; a pulley operatively connected with the stop motion, the latter comprising a shaft engaging member; a stop finger operatively connected with the stop motion; and a stop-motion control mechanism comprising a lever having oil compressing members in operative relation to the stop finger. 120

11. A stop-motion control lever having an 125 oil container; an oil filter therein; a rigid wall ported for flow of oil from the container to a side thereof; a rigid plug having a tang, a wall of the plug being opposed to and spaced apart from said wall; a fixed 130

sleeve having oil ports; a coiled spring on the plug tang; and a thimble inclosing the spring and slideable in the sleeve; in combination with a stop-motion mechanism and 5 a shaft to be stopped.

12. The combination of a rotary shaft; a stop-motion mechanism for the shaft and carrying a brake shoe; a pulley carried by the stop motion; a pressure plug for the 10 brake-shoe; a pressure-plug lifting lever; a stop finger for the stop motion; stop-motion control lever and a trip lever carried by the control lever in coöperative relation to the pressure-plug lifting lever; and means for 15 holding and compressing a shock absorbing volume of oil for taking up shock on actuation of the stop motion for arresting the rotation of the shaft.

13. The combination of a rotary shaft 20 with a stop-motion mechanism therefor; an oil supply mechanism comprising a pump; and a stop-motion actuating mechanism comprising a receptacle for receiving oil from the oil supply means for holding a 25 shock-absorbing volume of the oil and comprising other means for compressing such oil volume and thereby taking up shock on actuation of the stop-motion mechanism for stopping the shaft through coöperation of 30 the stop-motion actuating mechanism with the oil compressing means.

14. The combination of a sewing machine; a shaft-engaging stop-motion comprising an oil-cushion-forming mechanism 35 constructed and operating substantially as described; means whereby the oil cushion takes up the coupling shock in stopping the machine; means for automatically supplying oil to create and maintain the cushion; 40 and means for operating the stop-motion while the sewing machine is sewing.

15. The combination of stitch-forming

mechanisms comprising a driven shaft; a stop-motion for such shaft; a stop-motion-actuating mechanism comprising a chamber 45 for reception of oil; an oil pump operatively connected with such chamber; a plunger; and means actuated by the stop-motion for actuating the plunger, the latter working in said chamber and working in one direction against a body of oil maintained in the chamber by said pump.

16. The combination of a shaft with a stop motion therefor, said stop motion comprising members for engaging and disengaging the shaft to stop it, actuating means for said members, and an automatically-supplied oil cushion to prevent shock between coöperating members of the stop motion.

17. In the structure of claim 17, the stop-motion structure comprising a lever actuated by an adjustable lever.

18. The combination with a drive-shaft; of a stop-motion constructed and operable 65 for engaging and disengaging said drive-shaft; the stop-motion comprising liquid-cushion-forming means; means for supplying the liquid-cushion-forming means with cushion-forming liquid; and means for actuating the stop-motion.

19. The combination of a driven shaft; a stop-motion for such shaft; a stop-motion-actuating mechanism comprising a chamber for reception of oil; an oil pump operatively 75 connected with such chamber; thimbles; and means actuated by the stop-motion for actuating the thimbles, the latter working in said chamber and working in one direction against a body of oil maintained in the 80 chamber by said pump.

In testimony whereof I have hereunto set my hand this 3rd day of April, 1916.

JOHN PETER WEIS.
